Bradford E. Mattes, Esq.; Finn T. Simmensen, Esq.

(57) **CLAIM**

The ornamental design for a battery, as shown and described.

DESCRIPTION

FIG. 1 is a perspective view of the preferred embodiment of the battery showing our new design;

FIG. 2 is a perspective view of the rear thereof;

FIG. 3 is a front elevational view thereof;

FIG. 4 is a left elevational view thereof, the right side being identical;

FIG. 5 is a rear elevational view thereof;

FIG. 6 is a top view thereof;

FIG. 7 is a bottom view of thereof;

FIG. 8 is a first alternative embodiment showing a perspective view of the battery;

FIG. 9 is a perspective view of the rear of the first alternative embodiment;

FIG. 10 is a front elevational view thereof;

FIG. 11 is a left side elevational view thereof, the right side being identical;

FIG. 12 is a rear elevational view thereof;

FIG. 13 is a top view thereof;

FIG. 14 is a bottom view thereof;

FIG. 15 is a perspective view of the second alternative embodiment.

FIG. 16 is a rear perspective view thereof;

FIG. 17 is a perspective view of a third alternative embodiment.

FIG. 18 is a perspective view of the rear thereof;

FIG. 19 is a perspective view of a fourth alternative embodiment.

FIG. 20 is a perspective view of the rear thereof;

FIG. 21 is a perspective view of the fifth alternative embodiment; and,

FIG. 22 is a perspective view of the rear thereof.

Broken lines in the figures are for illustrative purposes only and form no part of the claimed design.
